EYEGLASS FRAME

Alexander Kono, Woodside, N. Y., assignor to Kono Manufacturing Co. Inc., Woodside, N. Y., a corporation of New York

Application April 10, 1956, Serial No. 40,994

Term of patent 14 years

(Cl. D57—1)

Fig. 1 is a top plan view of an eyeglass frame, showing my new design;

Fig. 2 is a front elevation thereof; and

Fig. 3 is a side elevation thereof.

In the drawings, the stippled portions represent contrasting colors on the frame.

I claim:

The ornamental design for an eyeglass frame, as shown and described.
